ABSTRACT

Cigars issuing three abreast from a pressing machine are split into three laterally spaced horizontal conveyors, collected into groups, fed through a head-punching apparatus, and thence fed towards a wrapping machine.

FIG. 4

CIGAR HANDLING APPARATUS

FIELD OF INVENTION

Tobacco; Cigar and Cigarette making.

PRIOR ART

Pietruska U.S. Pat. No. 3,225,774 Pressing Machines; Sundberg U.S. Pat. Nos. 2,800,133 and 2,854,986 Head Punchers; and Colton-Voice Cellophane Machines, e.g., Kath U.S. Pat. No. 2,044,947.

OBJECTS

Until comparatively recent times, cigars, after being made on a machine and color sorted, were placed in what are known in the trade as "dummy boxes," wherein they were retained under compression which gave them a somewhat square shape. Also, during this time the cigar paste sets so that they could be handled without appreciable danger of damage. After remaining under compression for about 24 hours, the cigars, for example, 13 to a layer, were stacked into the hopper of a head punching machine (for example, see the Sundberg patents, *supra*). Rows of cigars ejected from the head puncher onto a "walker" conveyor were fed to a banding and wrapping machine, for example, what is known as a Colton-Voice Cellophane machine; and the wrapped and banded cigars were finally packaged. Thus, although the making and wrapping processes were continuous, the dummy box step and the introduction of the cigars into the hopper of the head puncher were essentially batch process steps, so that the flow of cigars through the plant was continuous-batch-continuous.

The elimination of the dummy box step came about through the advent of cigar pressing machines, for example, see the Pietruska patent (*supra*). In one commercial form of the Pietruska machine, pressed cigars come off the output end in three columns, from which they were gathered and placed into the hoppers of the head punchers, the timing of the machines being such that one cigar pressing machine can feed three head punchers and three Cellophane machines. While one attendant can operate a Cellophane machine and handle wrapped cigars issuing therefrom, additional labor was needed to transport the cigars from the presser and load the head punchers. Hence, the savings in the nearly-complete conversion to continuous flow were not as great as anticipated.

The object now is to provide cigar handling machinery, including a novel conveying and feeding system between a presser and a head puncher, in which the handling of cigars, from the time they leave a pressing machine to the time they leave a Cellophane machine, is entirely automated.

One problem previously encountered in attempting to accomplish the above objective is that, if the three columns of cigars issuing from a pressing machine are conveyed directly forward to head puncher and wrapping or Cellophane machines, the columns are sufficiently close together that there was insufficient room for the head puncher and wrapping machines, and for the attendants to work around them. One attempt to divide the cigars in the columns and to spread them laterally involved a so-called "dealer," via which a first of three successive cigars was fed forwardly, a second was fed laterally in one direction, and a third was fed laterally in the opposite direction. However, this proved to be unduly complex and costly. According to this invention, the same objectives are accomplished in a much simpler manner.

These and other objects will be apparent from the following specification and drawings, in which:

FIG. 1 is a plan view of the cigar handling apparatus, including the output end of a typical cigar pressing machine and three head punchers;

FIG. 2 is a perspective view of the output end of a pressing machine, the forward conveyor and the two lateral conveyors;

FIG. 3 is a perspective view of the infeed and outfeed to and from a head puncher; and,

FIG. 4 is a diagram illustrating the control relationships of the cyclically-operating components.

Referring first to FIGS. 1 and 3, the output end of a Pietruska cigar pressing machine 2 delivers three abreast so that they form three series of cigars which will be designated 4a, 4b, 4c, to differentiate them according to the series in which they reside. Throughout the specification, the suffix letters *a*, *b* and *c* will also be used to differentiate similar components according to which line or series they are in. These cigars are to be fed to one of three head punching machines 6a, 6b, 6c, from whence they are fed to Colton-Voice Cellophane machines (not shown) in which they are wrapped, and usually banded also. While the head punching machines are shown in parallel positions in FIG. 1, it should be understood that they usually would be located in cascade or offset relationship so as to provide better access to them, and to provide more room for the Cellophane machines.

The details of the pressing machine 2 are not pertinent, except to note that the pressed cigars are gripped between spiced bars 8 on a chain conveyor, which bars spread as the chains pass over sprockets, and the cigars are ejected by pushers, not shown. Likewise, the details of the Cellophane machines are not relevant, other than that, in the present instance, cigars are fed to them by "walker" conveyors, i.e., those having two flat fixed bars upon which cigars rest, and one or more oscillating bars which lift the cigars up and move them along, step-by-step. A plunger feeds an endmost cigar off the end of this conveyor into the turret of the Cellophane machine. Assuming, for example, 13 cigars are to be simultaneously head-punched, a cycle counter provides a control signal each 13th stroke of the plunger. The subject matter of this invention starts with the provision of three platforms 10, 12 and 14 provided with riblike runners 16 which support the cigars ejected thereon and which reduce friction and facilitate sliding of the cigars thereover. Hold-downs are provided to prevent the cigars from piling up or rotting under one another. Two cigars can reside at one time on the end platforms 10 and 14 and more, for example, four in number, on the middle platform; and when a new cigar is pushed onto a platform, the outermost one is crowded off.

Referring now to the end column of cigars 4a and 4c, when the outermost of these is crowded off a platform, it slides onto a lateral conveyor 20a or 20c, each of which are formed by a pair of rubber belts 22, shaped in cross section like O-rings, and spaced slightly apart to form a valley in which cigars rest. Lateral conveyors are continuously driven in opposite directions by motors 24a, 24c. At the ends of the runs of lateral conveyors 20a or 20c, the cigars 4a or 4c feed onto forwardly moving end conveyor 26a or 26c; and when the cigars 4b in the middle column are crowded off their platform 12, they slide onto a forwardly moving middle conveyor 26b.

Conveyors 26a, 26b, 26c are essentially the same, except for length of run, and are constituted by three chains 28 (timing chains were found to be satisfactory) which run over conventional sprockets and are continuously driven by individual motors, not shown. The relative timings of the components are such that groups of cigars, generally indicated at 30a, 30b, 30c, accumulate at the ends of conveyors 26a, 26b, 26c.

At the end of the runs of conveyors 26a, 26b, 26c are dams 32 against which the leading cigars in groups 30a, 30b, 30c engage. Referring particularly to FIG. 3, dam 32 is fixed across the end of conveyor 26a, and it also slidably supports one side of a ram assembly indicated generally at 34a, 34b or 34c, each of which assemblies includes a crosshead 36 and an air actuated piston 38. Each time piston 38 is extended until its head 36 engages a stop 39, it pushes cigars in a group 30a, 30b or 30c off the end of a conveyor 26a, 26b or 26c into a receiving station, indicated generally at 40a, 40b, or 40c, which is at the start of a pusher-conveyor 42a, 42b or 42c.

Each pusher-conveyor includes an endless chain 44 with attachments 46 so spaced as to accommodate a group of cigars predetermined in number, such as 13, between them. Chain 44 is normally stationary, but with each actuation by its driver (not shown) is advanced a predetermined distance, i.e., the distance required to advance a group of cigars from receiving

station 40a to the head puncher station 47a. Optionally, a holdown roller 41 may be used to prevent the cigars from buckling up when the pusher-conveyor advances, which advance is relatively rapid.

With each advance of pusher-conveyor 42a, 42b, 42c, a group of cigars is moved to a head punching station 47a, 47b or 47c beneath a clamp bar 48 of the head puncher 6a, 6b or 6c whereupon the clamp bar lowers, locator nozzles 50 and hot rotating needles advance to hold and form holes in the cigar heads, and then retract. Then clamp bar raises and pusher-conveyor 42 advances so as to move the group of head-punched cigars forwardly from the head punching station and onto the walker-conveyor (not shown) which feeds the cigars to the Cellophane machine (also not shown). While this mechanism has been described as used to handle cigars from a Pietruska cigar pressing machine to three Colton-Voice Cellophane machines, it is adaptable for use in connection with other pressing and wrapping or packing machinery, and it can also be used with various types of head punchers.

FIG. 4 diagrammatically shows the chain of controls for the cyclically operating components. Operating with the plunger of the Cellophane machine is a preset counter. The lines designated "A," "B" and "C" indicate the succession of control signals from the preset counter. Assuming that the head puncher 6a is arranged to punch a bank of 13 cigars each cycle of operation, a preset counter is set to issue a control signal with every 13th stroke of the feed plunger. During the interval required for 13 strokes of the feed plunger, and due to the speeds of the presser 2, lateral conveyors 20a, 20c and the forward conveyors 26a, 26b, 26c, a row of 13 cigars will have accumulated in groups of 30a, 30b and 30c. In actual practice (by temporary stoppage of the Cellophane machine or by temporarily disabling the preset counter) a row of considerably more than 13 cigars is accumulated in groups 30a, 30b and 30c; and if larger stoppage of the Cellophane machine is desired, and if the buildup of cigars on a conveyor, such as 26b, becomes excessive, they can be diverted to a table 54a, 54b or 54c. With the 13th stroke of the infeed plunger, pusher-conveyor 42a advances a group of 13 cigars to the head puncher, and the latter starts its cycle of operation and ram assembly 34a moves forwardly to deposit a row of cigars into station 40a, and then the ram assembly immediately retracts. The succeeding 13 cigars accumulate against dam 32 while the head puncher completes its cycle of operation. When the next group of cigars is advanced to the head punch station, those cigars whose heads have been punched are advanced by the pusher-conveyor onto the walker (not shown).

I claim:

1. Apparatus for handling cigars discharged from a presser, wherein normally three cigars abreast oriented end-to-end are discharged generally horizontally away therefrom in a direction transverse to their lengths, said apparatus comprising

first, second and third horizontal platforms disposed side-by-side for receiving said cigars deposited thereon by said presser,
said platforms having free edges disposed away from said presser and off of which a previously deposited cigar is forced when another cigar is deposited by said presser,
first and second continuously running horizontal conveyors having input ends disposed adjacent the free edges of the

first and third platforms for receiving cigars therefrom, said first and second conveyors running in opposite directions lengthwise of the cigars deposited thereon and having output ends which are remote from said platforms,

third, fourth and fifth continuously running horizontal conveyors extending parallel to one another and having an input end respectively disposed for receiving cigars from the output end of the first horizontal conveyor, the second platform, and the output end of the second horizontal conveyor, each of said third, fourth and fifth conveyors having associated with the output ends thereof a dam against which a group of cigars normally accumulate,

means providing a receiving station laterally adjacent the output end of each of said dams,

a head puncher providing a head punch station along a path extending from each receiving station,

a ram for forcing groups of cigars from adjacent each dam to each respective receiving station,

pusher means for pushing groups of cigars along said path from each receiving station to each head punch station, and means for sequentially operating said ram, said pusher means, and said head puncher.

2. The combination claimed in claim 1, said platforms having ridges on the upper surface thereof extending in a direction transverse to the free edges thereof for reducing friction of cigars sliding thereacross.

3. The combination claimed in claim 1, said first and second horizontal conveyors each comprising a pair of endless belts generally circular in cross section and disposed adjacent one another to provide a trough for cradling said cigars.

4. Apparatus for handling cigars discharged from a presser, wherein cigars are discharged generally horizontally away therefrom in a direction transverse to their lengths, said apparatus comprising

a platform for receiving said cigars deposited thereon by said presser,
said platform having a free edge disposed away from said presser and off of which a previously deposited cigar is forced when another cigar is deposited by said presser, continuously running horizontal conveyor means having an input end disposed adjacent the free edge of the platform for receiving cigars therefrom, and having associated with an output end thereof
a dam against which a group of cigars normally accumulate,

means providing a receiving station laterally adjacent the output end of said dam,

a head puncher providing a head punch station along a path extending from the receiving station,

a ram for forcing groups of cigars from adjacent said dam to said receiving station,

pusher means for pushing groups of cigars along said path from said receiving station to said head punch station, and means for sequentially operating said ram, said pusher means, and said head puncher.

5. The combination claimed in claim 4, said platform having ridges on the upper surface thereof extending in a direction transverse to the free edges thereof for reducing friction of cigars sliding thereacross.
